UNITED STATES PATENT OFFICE

CHARLES M. YOUNG, OF TEN MILE TOWNSHIP, WHATCOM COUNTY, WASHINGTON

HAND CAN-TOP SEALER

Application filed July 22, 1929. Serial No. 380,030.

My invention relates to improvements in hand can-top sealers, the kind used in making the sanitary seal of tin can top to body, and has for an object to provide a hand can sealer of rigid construction in which the required resilience is supplied by the hand and arm of the operative.

Another object of my improvement is to provide a hand can sealer having neither eccentric, spiral nor cam surfaces of operation.

Another object of my improvement is to provide a hand can sealer designed for production on ordinary machine tools by mechanics of ordinary ability.

Another object of my improvement is to provide a hand can sealer which, with slight changes, is adaptable for sealing cans of various diameters and heights and yet be of convenient size for domestic hand use.

I attain these and other objects of my improvement with the mechanism illustrated in the accompanying two sheets of drawings in which Figure 1 is a top plan view, Fig. 2 is a front elevation of Fig. 1, Fig. 3 is a top plan view of one of the two similar roller housings segregated, Fig. 4 is a side elevation of Fig. 3, Fig. 5 is a top plan view of the reciprocatory head segregated, Fig. 6 is a bottom plan view of Fig. 5, Fig. 7 is an end elevation of Fig. 5 and Fig. 8 is a plan view in section on line 8—8 of Fig. 2.

Similar characters refer to similar parts in the several views. Certain parts are broken away to show other parts hidden thereby.

With more particular reference to the designated parts: A frame consisting of base bar 9 has table clamps 10, 10 fastened thereto and opposite uprights 11, 11 preferably integral with the ends thereof. To the upper ends of uprights 11, 11 is fastened top bar 12 which is carefully finished for a slide way.

Centrally disposed in base 9 is stud 13 parallel with uprights 11. An elevator slide bar consisting of thin end 14 and thick end 15 connected by incline 16 has longitudinal slot 17 therethrough, with which it is engaged with stud 13, is disposed flat side down on base 9. Stud 18 projects upward from near the thin end of the elevator slide. Lug 19 is fastened to the front side of base 9. Elevator

handle bar 20 is fulcrumed on lug 19 by bolt 21 through registering holes in bar and lug and has a hole near its inner end by which it engages stud 19 on the elevator bar. When in its illustrated full-line position thick part 15 of the elevator bar is adjacent stud 13 and by swinging handle 20 to its dotted position at 20', bar 14, 15 is moved to its dotted position at 14', 15' to bring its thinner end 14 adjacent stud 13. Elevator bar 14, 15 consists entirely of plane surfaces easy to finish in required exactness with ordinary machine tools in which it is an improvement over the usual cam or spiral-surface elevators common in other hand top sealers.

Ring 22 is placed on stud 13 to bear on the upper surface of the elevator bar and has a tapered bottom edge to conform to incline 16 and a flat bottom surface to bear on the upper surface of thick part 15 of the elevator bar. Ring 22 is the lower end of a column of variable length to support can base disc 31. On top of ring 22 washer 23 is shown over stud 13. To shorten the length of said column a thinner washer than 22 may be substituted therefor or it may be omitted. While to lengthen said column other washers of desired thickness may be added to washer 22 or a washer of standard thickness for a standard can may be substituted therefor. Internal threaded sleeve 25 is placed over stud 13 to bear on washer 23 or on ring 22 in the absence of said washer. Collar 24 has a threaded lower body to engage sleeve 25 and is placed over stud 13 engaged in said sleeve and is retained in desired location therein by set screw 26. The upper end of stud 13 is preferably below the middle of collar 24. Collar 24 in sleeve 25 provides for a fine adjustment of the length of said column and also may be used to replace washers somewhat thicker than 22 illustrated.

In the upper end of collar 24 a ball race is provided for balls 28. Thimble 29 has ring boss 27 near its upper end 30 which is extended through a central hole in base disc 31 which bears on said annular boss 27. Boss 27 has a ball race in its bottom surface for said balls 28, and when mounted thereon thimble 29 is extended in the upper end of

collar 24 in which it may revolve when boss 27 revolves on said balls. Thus the column is complete and provides a support for base disc 31 which, with the length of the column shown, moves down to its position at 31' when elevator bar 14, 15 is at 14', 15'.

Chuck disc 32 is centrally disposed on the lower surface of spindle flange 33 to which it preferably is fastened with screws. Spindle 34 is mounted for revolution in a central vertical hole through frame top bar 12 and has an enlargement 35 above flange 33 thereon to provide an end bearing against the bottom surface of said top bar 12. The upper end of the spindle 34 projects above bar 12 and is extended through driven bevel gear 36 to which it is removably fastened. Bevel gear 36 is engaged with driver gear 37 which is fastened on the inner end of drive shaft 38. Shaft 38 is mounted for revolution in brackets 39 and 40 which are fastened to top bar 12 and project upward therefrom. To the outer end of shaft 38 is fastened hand crank 42 used in turning said shaft by hand.

25 A reciprocatory head is preferably a channel in shape with web 41 and flanges *a*41, *a*41 is fitted to slide on frame top bar 12 to which it is applied from beneath. The head bar is engaged with bar 12 by two cross blocks 43, 43 disposed to bear on the upper surface of bar 12 and retained in place by taper pins *c*41, *c*41 through said flanges and blocks.

Through web 41 is central elongated hole 43 through which enlargement 35 of spindle 34 is extended. Also through web 41 are slots *a*43, *a*43 near the ends thereof, and in the upper surface of web 41 bordering slots *a*43 are recesses *b*43, *b*43. Projected downward from the ends of the head bar are ribs *b*41, *b*41, and across the bottom surface of web 41 are several pairs of grooves 44, 44; 45, 45; 46, 46; 47, 47 and 48, 48 the members of each pair of which are preferably disposed at equal distances from the longitudinal center 45 of the head bar.

There are two similar roll housings 49, 49, upper and lower bearing arms *b*49 and *a*49 of which have holes 52 in line through which are extended pins 56, 56 to mount said rolls. On the top of each of said housings 49 is transverse rib 50 to engage in any one of said pairs of notches, and through the housing body of each is bolt hole 51 parallel with holes 52. As shown in Fig. 2, one of said roll housings is fastened beneath head web 41 with rib 50 thereon engaged in one of grooves 46, to the left of chuck disc 32, and the other of said housings is similarly engaged with the other groove 46 to the right of said disc. Housings 49 are fastened in place by bolts 53 extended through slots *a*43 and holes 51 with bolt heads 54 seated in recesses *b*43 the width of which they fully occupy. Heads 54 are thin and the tops thereof are below the top 65 surface of web 41. Slots *a*43 and recesses

*b*43 are long enough to permit ribs 50 to be engaged with any one of said notches while said housings are disposed with arms *a*49, *b*49 thereof opposite each other.

On bearing pin 56 in the left-hand housing is mounted first roll 55 for revolution, and on bearing pin 53 in the right-hand housing is mounted second roll 57 for revolution. The grooves of these rolls are disposed in the plane of chuck plate 32 and adjacent the periphery thereof.

Stud 58 projects upward from the top surface of top bar 12 to which it is fastened in the transverse center thereof near and to the left of gear 36. In the upper edges of head flanges *a*41, *a*41 are notches 61, 61 opposite each other and in line with stud 58 when the head bar is in its central position shown in full lines in Figs. 1 and 2. Handle 59 has a hole in the end of its shank to engage stud 58 while said shank is engaged in one of notches 61. Preferably the edges of the shank where they bear on said flanges are arcuate as shown at 60, 60. By swinging handle 59 to its dotted position at 59', Fig. 1, head bar 41 is moved toward the right to its dotted position at 41' to bear on stop screw 62, see Fig. 2. And when said handle is swung toward the left to its position at 59'' head bar 41 is moved toward the left to 41'', see Fig. 1, to bear against stop screw 63, see Fig. 2. The position of said stop screws provides for the approach of said first and second rolls only to that proximity to chuck disc 32 which is needed to finish the work of each roll in sealing the can engaged by the disc.

The drawings are to scale for a machine to seal tin cans of standard sizes. In the operation of the machine the process is as follows: Elevator handle 20 is swung to 20' allowing ring 22 to move downward to bear on the thin part 14 of the elevator bar, which was moved by the handle from its full-line position to its dotted position at 14', 15', and bottom or base disc 31 moves down to 31'. The bottom of an unsealed can of the size for which the illustrated location of the adjustable parts of the machine is correct is placed on disc 31 with the unsealed top thereof in place on the can body and beneath chuck disc 32. Handle 20 is swung back to its first position moving thicker part 15 of the elevator beneath ring 22 and carrying disc 31 to its former full-line place. This forces the can lid snugly up against chuck disc 32 which has a nurled periphery, not indicated, causing it to bed into the wall of the recess usual in tin can tops, and securely connects the chuck disc with the can top which is held snugly in place on the can body. Handle crank 42 is turned, in direction most convenient, revolving the can top and body on balls 28. While one hand of the operative, the right hand for the illustrated set up of the machine, is turning

crank 42 the left hand grasps handle 59 forces it toward the right causing first roll 55 to press against the downwardly rolled can top edge which overhangs the outwardly rolled 5 upper edge of the can body. Revolution of the can continues and pressure on roll 55 is maintained till the first step in forming a joint between can top and body known as the sanitary seal is complete which is indicated 10 by stopping of farther right-hand movement of head bar 41 by the bearing of right-hand rib 641 on stop screw 62. While continuing the revolution of the can, handle 59 is now swung toward the left till second roll 57 contacts 15 with the partly finished seal and said pressure on handle 59 is continued till farther left-hand movement of head bar 41 is stopped by the contact of left-hand rib 641 with stop screw 63 when the seal is finished, 20 farther revolution of the can is stopped and it is removed from the machine after it has been lowered by swinging handle 20 to 20'.

Another unsealed can of the same size is placed in the machine and treated in a similar 25 manner till completely sealed when it is removed and its place taken by another and thus till all of the cans of the same size have been sealed.

To set the machine for another size of can, 30 spindle 34 is disconnected from gear 36 and removed together with chuck disc 32. Pins c41 are removed disconnecting cross blocks 43, a43. Head bar 41 is withdrawn downward and bolts 53 are removed releasing rolls 35 55 and 57 together with their housings. These housings are reset in accordance with the diameter of the cans to be sealed. Say this requires that ribs 50 be engaged in notches 48 to accommodate cans of the 40 largest diameter for which the illustrated machine was built. Bolts 53 are used to clamp the housings and rolls in the new location. Head bar 41 is restored to its operative position and blocks 43, a43 secured in 45 place. Spindle 34 is set in place and gear 36 fastened thereto. Chuck disc 32 is removed from flange 33 by removing its screw fastenings and a disc large enough for the cans next to be sealed screwed fast in its 50 place. If the illustrated position of base disc 31 is too high for the length of cans next to be sealed, the base column is lifted off of stud 13 and washer 23 removed to be replaced by a thinner one or the desired adjustment 55 is made by resetting collar 25. When the proper height of this column is attained a base disc suited to the new size of cans is put on top thereof in place of base disc 31.

The machine is now in proper adjustment 60 for a trial seal. The new size of can is installed between the base and chuck discs and clamped there by elevator block 15. A seal of the first can is made in the same manner as described above and then examined. If 65 the thickness of the metal in body and top

exactly correspond with that of the cans last sealed the new seal may be perfect. But a slight variation in this thickness will require a slight adjustment of the stop screws 62 and 63 which having been made the sealing of the larger cans may proceed. 70

In the same manner roll housings 49 may be engaged with any pair of said notches in the bottom of the head bar. If by mischance said housings are not engaged in a pair of 75 said notches, the wrong relative location thereof would make the machine inoperative.

The illustrated number and location of said notches provide for sealing cans of five different standard diameters which are, all 80 together, of four different lengths, all of which differences in length may be accommodated by possible adjustments of the base column.

Provision can be made in a similar and larger machine for sealing a larger number of standard cans without the size of the machine becoming too large for domestic use. 85

When the operative is left handed handle 59 is set on the opposite side of the machine 90 using the other notch 61 for engagement with the head flange.

It may be noted that the desired adjustments are such as may be made by those of moderate skill. This can hardly be said of 95 the usual machines of this character which have adjustments depending on the setting of eccentric collars.

In operating this machine the contacting roll is pushed back against the pressure of 100 the operative's hand once for each turn of the can when the increased thickness of metal at the lap of the body side seam passes beneath the roll. This back thrust is all absorbed by the operative's hand and arm 105 without subjecting the machine to additional strain.

In other hand machines this inequality in thickness of the work is usually provided for by a resilient member on which the strain is 110 excessive not infrequently resulting in deterioration of the resilient part.

Having thus disclosed my invention, what I claim as new therein and desire to secure by Letters Patent is,

1. A can-top sealer consisting of a frame attachable to a bench having a bottom frame bar a top frame bar and two side frame uprights connecting said bottom and top bars rigidly together, a head bar mounted for reciprocation on said top frame bar, a vertical spindle mounted for revolution in central bearings on said top frame bar, a chuck disc adapted to engage a can top fastened to the lower end of said spindle concentric therewith and revoluble thereby, a grooved first sealing roll mounted for revolution on a vertical shaft fastened to said head bar adjacent said chuck disc having said groove thereof in the plane of said chuck disc, a grooved 120

second-sealing roll mounted for revolution on a vertical shaft fastened to said head bar adjacent said chuck disc opposite said first-sealing roll having the plane of said groove thereof in the plane of said chuck disc, a vertical stud on the bottom frame bar projected upward in the axis of the vertical spindle, elevator means mounted on the stud to bear on the bottom frame bar, a nut around 10 the stud supported on the elevator means, an externally threaded sleeve engaged threadwise in the nut mounted on the stud, a can base disc adapted to mount a can thereon having a hub engaged with the upper end 15 of the sleeve mounted thereon for revolution in the axis of the vertical spindle, means to operate said elevator means beneath the nut to raise, retain and lower the can base disc, and means to revolve the spindle and reciprocate the head bar.

2. A can-top sealer consisting of a frame attachable to a bench having a bottom frame bar a top frame bar and two side frame uprights rigidly connecting said top and bottom frame bars, a head bar having transverse grooves at standard distances apart in its bottom surface mounted for reciprocation from below on said top frame bar, a vertical spindle mounted for revolution in central 25 bearings on said top frame bar, a chuck disc adapted to engage a can top fastened to the lower end of said spindle for revolution therewith, two roll housings fastenable to said head bar at variable locations on each 30 side of said spindle each having a rib on the top thereof engageable in any one of said head bar grooves, shafts fastened in said roll housings parallel with said spindle when in operative position, a crimping roll mounted 35 for revolution in each of said housings each having an annular groove therein operatively in the plane of said chuck disc, a can-base disc adapted to mount a can thereon mounted for revolution on said bottom frame 40 bar with its axis of revolution coinciding with the axis of said spindle, means to elevate said base disc to clamp a can mounted thereon between the same and said chuck disc, means to vary the clamping distance 45 between said chuck and base discs, means to revolve said spindle, means to reciprocate said head bar and retain each of said rolls in turn with crimping pressure against the rolled edge of a can top engaged on said 50 chuck disc, and means to depress said base disc.

3. In a can-top sealer in combination, a spindle, bearings to mount said spindle vertically for revolution, a chuck disc to engage 55 a can top fastened on the lower end of said spindle for revolution therewith, a frame adapted to fasten to a bench rigidly fastened to said spindle bearings, a stud fastened to said frame beneath said spindle with its axis coinciding with the axis of said spindle, an

extendible column mounted on said stud revolvable and reciprocable thereon, a can-base disc to mount a can mounted for revolution on the upper end of said column concentric with said stud, an elevator bar bearing on 60 said frame having a longitudinal slot therethrough engaging said stud beneath the lower end of said column said bar consisting of a thicker and a thinner end having relatively stepped top surfaces with an intervening 65 central body having an inclined plane top surface connecting said stepped surfaces adapted to be moved substantially longitudinally in one direction beneath said column to elevate the same from a position of bearing 70 on said thinner end of said bar over said incline to a position of bearing on the thicker end thereof and to be moved in the opposite direction to depress said column from bearing 75 on said thicker bar end to bearing on the 80 thinner end thereof, means to reciprocate said elevator bar, two sealing rolls mounted for revolution on opposite sides of said chuck disc having annular grooves therein disposed in the plane of said chuck disc, means to 85 mount said rolls for revolution, means to separately move each of said rolls to proximity to the periphery of said chuck disc, and means to revolve said spindle.
